UNITED STATES PATENT OFFICE.

JOHN HENRY JENNER, OF LEAVENWORTH, INDIANA.

ADJUSTABLE WRENCH.

1,214,473.

Specification of Letters Patent. Patented Jan. 30, 1917.

Application filed May 22, 1916. Serial No. 99,169.

To all whom it may concern:

Be it known that I, JOHN HENRY JENNER, a citizen of the United States, residing at Leavenworth, in the county of Crawford 5 and State of Indiana, have invented certain new and useful Improvements in Adjustable Wrenches; and I do declare the following to be a full, clear, and exact description of the invention, such as will enable others skilled in the art to which it appertains to 10 make and use the same.

This invention relates to improvements in adjustable sliding jaw wrenches, said improvements being applicable to both pipe 15 and nut wrenches.

The principal object of the invention is to provide a wrench of this character with means whereby the sliding jaw may be quickly and easily adjusted and held in this 20 adjusted position until manually released.

An additional object of the invention is to provide a simply constructed wrench having a small number of parts and one which will be very efficient in operation and use.

With these general objects in view, my invention resides in the novel features of construction, combination and arrangement of parts which will hereinafter be more particularly described and claimed.

In the accompanying drawings: Figure 1 is a side elevation of a wrench constructed in accordance with my invention, showing the parts in their normal position; Fig. 2 is an edge view of the tool shown in Fig. 1; Fig. 3 is a vertical section showing more particularly the arrangement of the parts when in their normal inactive position; Fig. 4 is a similar view showing the position of the various parts of the wrench when the same 40 is in its gripping position; Fig. 5 is also a view similar to Fig. 3 showing the lever retracted so that the movable jaw may be adjusted; Fig. 6 is a horizontal section taken on the line 6—6 of Fig. 3; and Fig. 7 is a 45 detail perspective view of the upper end of the bell crank lever showing the pawl 14 and its coöperating parts.

In the preferred embodiment illustrated, the numeral 1 designates a movable jaw 50 member having a shank 2 extending therefrom which is slideable vertically in a guide formed in a stationary jaw member 3. This member 3 is preferably formed of heavy gage sheet metal bent into channel-shape as 55 shown and having a stationary jaw 4 secured therein adjacent one end thereof. The

shank 2 has its inner or free end portion reduced as shown at 5 and provided with ratchet teeth 6, the extreme free end of this shank also having a stop 7 which is used to 60 prevent the movable jaw member from sliding out of the stationary member 3.

The sides of the channeled portion of the jaw member 3 are shaped adjacent their connection with the stationary jaw 4 to form 65 ears 8 having aligned pivot openings 9 therein. The short arm 10 of a bell-crank lever 11 is disposed between the ears 8 and pivoted at its end thereto by a pivot pin 12 which extends through the openings 9 and 70 through additional openings in the lever. The long arm 13 of the bell crank lever 11 and the shank portion of the member 3 form together a handle for the wrench.

The pivoted end of the bell crank lever including the short arm 10 is bifurcated and designed to receive between the furcations thereof an arcuately shaped pawl 14, one of whose ends is pivoted to the lever 11 at the intersection of the short and long arms 10 80 and 13 respectively, while its opposite end has a head 15 formed thereon, on the straight face of which are provided one or more ratchet teeth for engagement with the teeth 6 on the shank of the movable jaw member 85 1. A curved leaf spring 16 carried by the long arm 13 of the lever 11 engages the outside face of the pawl 14 and tends to force the same toward the teeth 6 while at the same time causing the lever to move outwardly 90 away from the stationary jaw member 3. From the drawings it will be seen that the spring 16 is secured at one end to the long arm 13, the other end being movable between the bifurcated ends of the lever. I have also 95 provided an additional leaf spring 17 secured to the stationary jaw 4 and so disposed that its free end will engage the pawl 14 adjacent its fulcrumed point and cause the bell crank lever and the parts carried thereby to move inwardly around the pivot pin 12, thus holding the pawl 14 in normal engagement with the teeth 6 as will later be more 100 fully explained.

In addition to the above features, I have 105 equipped this improved wrench with means for disengaging the pawl 14 from the teeth 6 by moving the long arm 13 of the lever 11 outwardly away from the member 3. This consists of a dog 18 pivoted intermediate its 110 ends upon the pivot pin 12. One end of the dog is provided with a cam face 19 which en-

gages the seat formed by the inner curved portion of the pawl 14, while its other end is shaped to provide a finger 20.

The dog 18 is normally in engagement 5 with the pawl 14 at two points, the cam 19 contacting with the curved portion or seat thereof at 21, while the base of the finger 20 bears against the pivoted end thereof as seen at 22. This normal position of the parts 10 is shown in Fig. 3, where it will also be seen that the spring 16 engages the outer face of the pawl 14 and the spring 17 the inner pivoted end thereof. This spring 16 while it tends to force the pawl into engagement with 15 the teeth 6, is prevented from doing so because of the action of the dog 18. Thus the teeth of the pawl and those on the movable jaw member are held in engagement by the action of the spring 17, which, bearing 20 against the inner pivoted end of said pawl moves the bell crank lever 11 and the parts carried thereby around the pivot 12. The spring 16 serves to force the arm 13 of the lever 11 outwardly when the teeth are engaged 25 as shown in this figure, or when the parts are as illustrated in Fig. 4. When, however, a nut or other article is to be gripped between the jaws of the wrench, the parts are caused to assume the positions 30 shown in Fig. 4, the long arm 13 being moved toward the member 3. This movement of the arm causes the bell crank lever 11 to move around the pivot 12, carrying with it the pawl 14, which in turn forces the 35 movable jaw member inwardly to tightly grip the article. In this position, the dog 18 and the spring 17 have become inactive, the former having its cam 19 disengaged from the pawl so that the spring 16 is permitted 40 to act thereon and hold it in contact with the teeth 6. Thus the pawl is held in engagement with the teeth in the shank 2 both when the parts are in their normal position as shown in Fig. 3, and when in their 45 gripping position as in Fig. 4, first by the action of the spring 17, and lastly by the spring 16.

To adjust the movable jaw member, the long arm 13 of the lever 11 is moved outwardly to disengage the teeth on the head 50 15 from those in the shank 2 as shown in Fig. 5. From this figure it will be seen that the pawl 14 and the dog 18 are in the same position with respect to each other as when 55 the lever 11 is in its normal position as illustrated in Fig. 3. In other words, the cam 19 of the dog engages the pawl at 21, the latter being held in contact therewith by the spring 16, and the base of the finger 60 20 contacts at 22 with the inner pivoted end of the pawl adjacent its pivot, thus limiting the action of the spring 16 and preventing the inward movement of the pawl thereby. But, although the parts 16 85 and 18 remain the same with respect to each

other, the pawl is moved out of engagement with the teeth 6 due to the fact that the short arm 10 of the lever 11 is moved inwardly against the tension of the spring 17. As soon as the jaw 1 has been adjusted 70 outwardly, the arm 13 is released, and the spring 17 throws the lever into its normal position with the pawl 14 engaging the teeth 6, whereupon the wrench is ready to grip the article to be operated upon. 75

It is desired to lay particular stress upon the operation of the spring 17 inasmuch as it holds the pawl 14 in engagement with the ratchet teeth 6 and prevents the movable jaw member 1 from sliding outwardly 80 away from the other parts of the wrench when the same is held in any other position than that shown in the drawings. Were it not for this spring, the lever 11 and the parts carried thereby would have a tendency 85 to move about the pivot 12 and prevent proper operation of the wrench. Furthermore, the dog 18 which is used for releasing the pawl 14 from the teeth 6 when the lever is moved outwardly, is also an 90 extremely important part of the invention.

I claim:

1. A wrench of the class described comprising a movable jaw member having ratchet teeth on its shank, a stationary jaw 95 member having a guide to receive the shank, a lever pivoted to the stationary jaw member, a pawl carried by said lever for engagement with said ratchet teeth, means for forcing said pawl into normal engagement 100 with said ratchet teeth, and a pivoted dog for co-operation with said pawl to move the latter out of engagement with the teeth when said lever is moved in one direction.

2. A wrench of the class described comprising a movable jaw member having ratchet teeth on its shank, a stationary jaw member having a guide to receive the shank, a lever pivoted to the stationary jaw member, a pawl carried by said lever for engagement with said ratchet teeth, a pair of 110 springs engaging said pawl, and a dog, said dog forcing said pawl out of engagement with said teeth when the lever is moved in one direction. 115

3. A wrench of the class described comprising a movable jaw member having ratchet teeth on its shank, a stationary jaw member having a guide to receive the shank, a lever pivoted to the stationary jaw member, a pawl carried by said lever for engagement with said ratchet teeth, a pair of springs engaging said pawl, and a dog pivoted intermediate its ends and having a cam face on one end engaging a seat in said 120 pawl, the dog forcing said pawl out of engagement with the teeth when the lever is operated in one direction. 125

4. A wrench of the class described comprising a movable jaw member having 130

ratchet teeth on its shank, a stationary jaw member having a guide to receive the shank, a bell crank lever pivoted at one end to the stationary jaw member, a pawl pivoted to 5 the lever for engagement with said ratchet teeth and having a seat therein, a spring on said stationary jaw member for engagement with said pawl for holding the same normally in engagement with said teeth, an 10 additional spring for forcing said lever outwardly, and a dog pivoted intermediate its ends and having a cam face on one end for engagement with said seat, said dog forcing

said pawl out of engagement with the teeth when the lever is actuated in one direction, 15 said dog and the first mentioned spring being inactive when the lever is moved in the other direction.

In testimony whereof I have hereunto set my hand in the presence of two subscribing 20 witnesses.

JOHN HENRY JENNER.
